Primary Examiner — Ruth McInroy(74) Attorney, Agent, or Firm — Husch Blackwell LLP(57) CLAIM

We claim the ornamental design for a baseball catcher's helmet, as shown and described.

DESCRIPTION

FIG. 1 is a perspective view of baseball catcher's helmet, showing my new design;

FIG. 2 is a front view thereof;

FIG. 3 is a back view thereof;

FIG. 4 is a right view thereof;

FIG. 5 is a left view thereof; and,

FIG. 6 is a top view thereof.

The subject matter shown in dashed lines is for illustrative purposes and forms no part of the claimed design.
